(57) **CLAIM**

The ornamental design for a control panel as shown and
described.

DESCRIPTION

FIG. 1 is a front perspective view of a control panel,
according to the present invention;

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof; and,

FIG. 8 is a perspective view thereof, showing an exemplary
automated litter device with a bezel about an entry opening
that the control panel is affixed to.

The broken lines showing a litter device in FIG. 8 depicts
environmental subject matter and forms no part of the
claimed design. The remaining dash-dash broken lines in the
figures depict portions of the control panel that form no part
of the claimed design.

1 Claim, 6 Drawing Sheets

Related U.S. Application Data

and a continuation-in-part of application No. 29/755,931, filed on Oct. 23, 2020, now Pat. No. Des. 975,939, and a continuation-in-part of application No. 29/755,935, filed on Oct. 23, 2020, now Pat. No. Des. 975,383, and a continuation-in-part of application No. 29/749,988, filed on Sep. 10, 2020, now Pat. No. Des. 976,501, said application No. 29/755,931 is a continuation-in-part of application No. 16/428,433, filed on May 31, 2019, now Pat. No. 11,399,502.
